MACHINE FOR REMOVING FLOOR COVERINGS

Walter E. Overell, Flintridge, Calif.

Application February 28, 1935, Serial No. 8,782

14 Claims. (Cl. 164—83)

The present invention relates to new and useful improvements in a machine for removing coverings, such as linoleum or the like, which have been cemented to floors.

5 An object of the invention is to provide a machine which may be operated to cut the floor covering into strips and to sever the cement bond so as to progressively remove the covering from the floor in strips.

10 A further object of the invention is to provide a machine of the type referred to wherein a cutting blade is vibrated to sever the cement bond between the floor and the covering.

A still further object of the invention is to provide 15 a machine of the type referred to wherein the cutter for severing the cement bond may be raised and lowered and the inclination thereof shifted at the will of the operator.

A still further object of the invention is to provide 20 in a machine of the type referred to, a means whereby the supporting base may be moved forward during the cutting operation.

The above and other objects of the invention will in part be obvious and will be hereinafter 25 more fully pointed out.

In the accompanying drawings:

Figure 1 is a side elevation of the machine.

Figure 2 is a top plan view of the cutting device and the supporting base.

30 Figure 3 is a front elevation of the cutting device and the supporting base.

Figure 4 is a fragmentary side elevation of the supporting base with the cutting device in a raised position.

35 Figure 5 is a view similar to Fig. 4, with the cutting device in a lowered position.

Figure 6 is a sectional view taken along line 6—6 of Fig. 2.

40 Figure 7 is a diagrammatic view of the cutter actuating cams.

The invention relates generally to a machine for removing floor coverings, such as linoleum or other hard-surfaced coverings, from floors to which they have been cemented, and generally 45 contemplates the provision of a supporting base on which is mounted a cutter head and means for operating said cutter head. The invention also provides means whereby the supporting base may be advanced to progressively remove the floor covering. The cutting device includes means for severing the cement bond between the floor and the covering and also means for cutting the covering whereby it may be removed in strips. There is also provided means for adjusting the inclination 50 of the cutting device whereby to permit the

machine to operate where there are variations in the thickness of the covering and also any unevenness in the floor itself.

The invention will now be described in detail, reference being had to the accompanying drawings. The supporting base consists of a pair of side members 11, 12, each of which is provided with an upstanding front end portion 11a, 12a, respectively. The side members are held together by a rear plate 13 suitably secured thereto and by a front plate 14 which is secured to the end portions 11a, 12a and to the side members 11, 12 by bolts 16 or the like. A pair of side plates 17, 18 are secured to the upper edges of the side members 11, 12 respectively. Secured to the plates 17, 18 is 10 a handle and control supporting device which consists of pairs of arms 19, 20. The arms 19 are joined by a handle roller 21. A plate 22 secured to the arms 20 has mounted thereon three spaced notched quadrants 23, each of which has pivotally mounted thereon a latch handle for engaging the notches therein. The two outer handle levers 24 are connected by rods 25, 25a to the free ends of levers 26, 26a respectively, which are pivotally mounted on a bracket 27 secured to the frame 10. The center lever 25b is connected by a rod 28 to a lever 29 which is also pivotally mounted on the bracket 27. 15

The side members 11, 12 are provided with openings 30, 30a in which are mounted housing members 31, 31a respectively which carry suitable anti-friction bearings 32 for the ends of a shaft 33. A belt wheel 34 carried by the shaft 33 is connected by a belt 34a to an electric motor 35 which is supported on a platform 36 pivotally connected to the frame 10 between the side plates 17, 18. There is provided suitable spring means 36a for taking up any slack in the belt 34a. A plurality of weights 37 are mounted on the base in order to provide a suitable inertia mass for a foundation 40 from which to move the blade forward and thus render the operation of the machine more effective.

A pair of flexible plates or supports 38, 38a are suitably mounted on the plate 14. Each plate carries a bracket 39, 39a at the free end thereof on which are pivotally mounted levers 40, 40a respectively. One end of each of the levers 40, 40a is connected by a link 41, 41a (see Fig. 6) respectively to the levers 26, 26a. The opposite ends of the levers 40, 40a are pivotally mounted on pins 42, 42a respectively, which are carried by bracket arms 43, 43a on the clamping plate 44. An arm 45 rigidly mounted on the clamping plate 44 extends rearwardly between the brackets 43, 43a 50 55

and is connected by a link 46 (see Fig. 6) to the lever 29.

The shaft 33 carries eccentrics 47, 47a which are provided with grooves for the reception of balls 48 disposed between the grooved raceways 49, 49a on the eccentric straps 50, 50a respectively. The eccentric straps are provided with connecting rods 51, 51a which are pivotally mounted on the pins 42, 42a respectively whereby to vibrate the clamping plate 44. Counterweights 52, 52a are carried by the shaft 33 in order to dampen vibration. As shown diagrammatically in Fig. 7, the eccentrics 47, 47a are set slightly apart, that is, one is advanced with respect to the other so as to advance one end of the clamping plate 44 ahead of the other end alternately and thus impart an oscillatory movement thereto. By setting the eccentrics evenly, however, the clamping plate 44 may be given a straight reciprocatory movement.

The clamping plate 44 carries a horizontal cutter blade 53 for severing the cement bond between the covering and the floor. A pair of vertical cutter blades 54, 54a are suitably mounted on the ends of the clamping plate 44 for cutting the floor covering into strips.

The supporting base 10 is provided with brackets 55, 55a which carry rollers 56, 56a respectively. These rollers do not touch the surface when the base is resting on the side members 11, 12, but the machine may be moved about by grasping the handle 21 and tilting the machine backwards so that it will be supported by said rollers 56, 56a.

A platform 57 is provided with serrations 58 which may be embedded in the floor covering to afford a firm engagement therewith. An operating lever 59 is pivotally mounted on the platform 57 and is connected to the supporting base 10 by links 60. A motor control switch 61 is mounted on the arms 20 whereby the operator may conveniently control the operation of the cutting device.

In operation, by tilting the supporting base to rest on the rollers 56, 56a, the machine may be moved to a proper starting position where the base is then set down to rest on the side members 11, 12. To start an initial cut in the floor covering, the center latch handle 25b is moved to the position shown in Fig. 1. This movement of the lever 25b operates through the rod 28 to raise the lever 29 and the link 46 which operates through the arm 45 to turn the clamping plate 44 about the pivot pins 42, 42a in order to direct the cutting blades downwardly. The switch 61 is then thrown on to start the motor 35 which rotates the shaft 33 through the driving belt 34a. The eccentrics 47, 47a cause a reciprocation of the clamping plate 44 through the connecting rods 51, 51a which are pivotally connected to the pins 42, 42a carried by the clamping plate. Because of the offset position of the eccentrics relative to one another, the cutting head will be caused to oscillate although, as stated heretofore, a straight reciprocatory movement may be imparted thereto by proper adjustment of the eccentrics. After the initial cut in the floor covering has been made, the lever 25b is moved upwardly to reduce the inclination of the cutting blades. The side handle levers 24 may be moved to various positions in order to adjust the depth or inclination at which the cutter head operates after the initial cut has been made. When the handle levers 24 are in the position shown in Fig. 1, the blade clamping plate is in the position shown in Fig. 4. When the levers 24 are moved in a clockwise direction, the levers 26, 26a will be

raised by the rods 25, 25a and this will raise the links 41, 41a. This movement of the links 41, 41a will move the levers 40, 40a about their pivotal connecting point on the brackets 39, 39a respectively, causing the ends which are pivotally mounted on the pins 42, 42a respectively to descend, thus lowering the cutter head. In this way, the position of the cutting blades on the clamping plate may be varied according to the thickness of the floor covering. Similarly a movement of only one of the outer levers 24 will effect a change in the angle of the clamping plate 44, in order to operate over floors having an uneven or sloping surface. The operator, standing on the platform 57, can effect all the above changes. In order to progressively cut the floor covering, the operator can advance the entire supporting base 10 by pushing on the lever 59 which operates through the links 60 to advance the base and cutting head.

It is to be noted that the entire cutting head is supported by the resilient plates 38, 38a which permit the oscillatory movement thereof. When either end of the clamping plate 44 is retracted by the corresponding connecting rod, the resilient plate adjacent the same end will be forced toward the front plate 14, thus increasing the initial tension therein so that, at the next forward stroke of that end of the clamping plate 44, the stored energy in the adjacent resilient plate 38 will aid in forcing the cutter head forward. The cutter head, while supported by the resilient plates 38, 38a, is pivotally mounted on the ends of the levers 40, 40a which in turn are pivotally mounted on the brackets 39, 39a carried by the resilient supporting plates 38, 38a respectively.

It will be obvious from the foregoing description that an extremely simple and efficient machine is herewith provided. It is to be clearly understood that minor changes in the details of construction and arrangement of parts may be made without departing from the scope of the appended claims.

Having thus described the invention, what I claim as new and desire to secure by Letters-Patent, is—

1. A machine for removing coverings cemented to floors, comprising a supporting base, a cutter head carried thereby, vertical cutters mounted on said head for severing the covering into strips, and a cutting blade mounted on said head and extending between said vertical cutters for severing the cement bond between the floor and the covering.

2. A machine for removing coverings cemented to floors, comprising a supporting base, a cutter head carried thereby, means for vibrating the cutter head, vertical cutters mounted on said head for severing the covering into strips, and a cutting blade mounted on said head and extending between said vertical cutters for severing the cement bond between the floor and the covering.

3. A machine for removing coverings cemented to floors, comprising a supporting base, a cutter head carried thereby, means for vibrating said head, vertical cutters mounted on said head for cutting the covering into strips, a cutting blade mounted on said head and extending between said vertical cutters for severing the cement bond between the covering and the floor, and means for advancing the supporting base whereby to progressively remove the floor covering.

4. A machine for removing coverings cemented to floors, comprising a supporting base, a cutter head, means for vibrating the cutter head,

- vertical cutters mounted on said head for severing the covering into strips, a cutting blade mounted on said head and extending between said vertical cutters for severing the cement bond between the floor and the covering, means for raising and lowering the cutter head and changing the inclination thereof, and means for advancing the supporting base whereby to progressively remove the floor covering.
- 5 10 15 20 25 30 35 40 45 50 55 60 65 70 75 80 85 90 95
5. A machine for removing coverings cemented to floors, comprising a supporting base, a cutter head, means for mounting said head on said supporting base for movement relative thereto, a shaft journaled in the sides of said base, means for rotating said shaft, means including eccentrics carried by said shaft for imparting an oscillatory movement to said head, vertical cutters mounted on said head for severing the covering into strips, and a cutting blade extending between said cutters for severing the cement bond between the covering and the floor.
6. A machine for removing coverings cemented to floors, comprising a supporting base, a pair of resilient plates mounted on said base for limited movement relative thereto, a cutter head, means for pivotally supporting said head on said plates, means for oscillating said cutter head, vertical cutters mounted on said head for severing the covering into strips, and a cutting blade extending between said vertical cutters for severing the cement bond between the covering and the floor.
7. A machine for removing coverings cemented to floors, comprising a supporting base, a pair of resilient plates mounted on said base for limited movement relative thereto, a pair of levers pivotally mounted on the ends of said resilient plates, a cutter head, means for pivotally mounting said cutter head on the forward ends of said levers, means connected to the opposite ends of said levers for adjusting said cutter head, vertical cutters mounted on said head for severing the covering into strips, a cutting blade extending between said vertical cutters for severing the cement bond between the covering and the floor, and means for vibrating said cutter head whereby to remove the covering in strips.
8. A machine for removing coverings cemented to floors, comprising a supporting base, a pair of resilient plates mounted on said base for limited movement relative thereto, a pair of levers pivotally mounted on the ends of said resilient plates, a cutter head, means for pivotally connecting said head to the forward ends of said levers, a second pair of levers pivotally mounted on said base, links connecting said first-named levers with said second pair of levers, means connected to the free ends of said second pair of levers for adjusting the height of said head and the inclination thereof, vertical cutters mounted on said head for severing the covering into strips, a cutting blade extending between said vertical cutters for severing the cement bond between the covering and the floor, and means for vibrating said head whereby to remove the covering in strips.
9. A machine for removing coverings cemented to floors, comprising a supporting base, a pair of resilient plates mounted on said base for movement relative thereto, a pair of levers pivotally mounted on the ends of said resilient plates, a cutter head, means for pivotally mounting said head on the forward ends of said levers, means connected to the opposite ends of said
- levers for adjusting the height and inclination of said head, an arm extending rearwardly from said head, means connected to the free end of said arm for adjusting the vertical angle of said head, vertical cutters mounted on said head for severing the covering into strips, a cutting blade extending between said vertical cutters for severing the cement bond between the covering and the floor, and means for vibrating the cutter head whereby to remove the covering in strips.
10. A machine for removing coverings cemented to floors, comprising a supporting base, means for advancing the supporting base, a cutter head, means for mounting said cutter head on said base for movement relative thereto, vertical cutters mounted on said head for severing the covering into strips, a cutting blade extending between said vertical cutters for severing the cement bond between the covering and the floor, a shaft journaled in the sides of said base, means for rotating said shaft, eccentrics carried by said shaft and offset with respect to one another, and means connecting said eccentrics with said head whereby to impart an oscillatory movement thereto.
- 15 20 25 30 35 40 45 50 55 60 65 70 75 80 85 90 95
11. A machine for removing coverings cemented to floors, comprising a supporting base, a cutter head mounted on said base for limited movement relative thereto, means for vibrating said head, vertical cutters mounted on said head for severing the covering into strips, a cutting blade extending between said vertical cutters for severing the cement bond between the covering and the floor, a stationary platform on which an operator stands, and means connecting said platform to said base and operable from said platform for advancing said base whereby to progressively remove the floor covering in strips.
12. A machine for removing covering cemented to floors, comprising a supporting base, a cutter head carried thereby, means for imparting an oscillatory movement to said cutter head, vertical cutters mounted on said head for severing the covering into strips, and a cutting blade mounted on said head and extending between said vertical cutters for severing the cement bond between the floor and the covering.
13. A machine for removing covering cemented to floors, comprising a supporting base, a cutter head, means including resilient plates for mounting said head on said base for limited movement relative thereto, means for imparting an oscillatory movement to said cutter head, vertical cutters mounted on said head for severing the covering into strips, and a horizontal cutting blade mounted on said head and extending between said vertical cutters for severing the cement bond between the floor and the covering.
14. A machine for removing covering cemented to floors, comprising a supporting base, a cutter head, means for mounting said cutter head on said base for limited movement relative thereto, means for imparting an oscillatory movement to said cutter head, vertical cutters mounted on said head for severing the covering into strips, a horizontal cutting blade mounted on said head and extending between said vertical cutters for severing the cement bond between the floor and the covering, and means for advancing said supporting base whereby to progressively remove the floor covering.
